Inventor:
J. H. BOWLBY,

Monroe E. Miller
Attorney.

UNITED STATES PATENT OFFICE.

JAMES H. BOWLBY, OF SAVONBURG, KANSAS.

TOURIST BED.

Application filed November 20, 1923. Serial No. 675,827.

To all whom it may concern:

Be it known that I, JAMES H. BOWLBY, a citizen of the United States, residing at Savonburg, in the county of Allen and 5 State of Kansas, have invented certain new and useful Improvements in Tourist Beds, of which the following is a specification, reference being had therein to the accompanying drawing.

10 The present invention relates to tourist beds, and aims to provide a novel and improved collapsible bed and shelter to be carried by automobiles and other vehicles, the device being particularly useful for 15 tourists to provide adequate and convenient accommodations for sleeping while camping or touring.

Another object of the invention is the provision of a foldable bed frame that can 20 be folded within small space adjacent to the vehicle, and which has automatically folding legs to support the frame from the ground when the frame is unfolded.

A further object is the provision of a 25 casing for housing the bed frame, which will also provide a cover or shelter for the bed when the parts are unfolded for use.

Another object is the provision of such a 30 casing having combined therewith a novel folding shelter or roof for the bed.

A still further object is the provision of a novel means for holding the folded bed frame in the casing, and for conveniently releasing said frame when it is desired to 35 unfold same.

The invention has for another object the provision of a casing for the bed frame which can also provide a table.

With the foregoing and other objects in 40 view, which will be apparent as the description proceeds, the invention resides in the construction and arrangement of parts as hereinafter described and claimed, it being understood that changes can be made within 45 the scope of what is claimed, without departing from the spirit of the invention.

The invention is illustrated in the accompanying drawings, wherein—

Figure 1 is a side elevation of the structure in unfolded position, ready for use 50 as a bed, portions being broken away.

Fig. 2 is an end view of the device, with the parts in the position as shown in Fig. 1, portions being broken away and shown 55 in section.

Fig. 3 is a horizontal section on the line 3—3 of Fig. 2.

Fig. 4 is a cross section of the device when folded, taken on the line 4—4 of Fig. 5. 60

Fig. 5 is a section on the line 5—5 of Fig. 4.

Fig. 6 is an end view of the device showing the cover of the casing in position to 65 serve as a table top.

Fig. 7 is an end view of the folded bed frame, showing a modified means for holding same in place.

The casing, which may be constructed of sheet metal or other suitable material, comprises the body 10 and front section or cover 11, which are hingedly connected at their upper edges by the hinges 12, whereby the cover 11 can be swung forwardly and upwardly. The casing is elongated longitudinally to be disposed at one side of the automobile or other vehicle, and is of suitable size. The body 10 of the casing is rigidly secured to the vehicle by any suitable means. As shown, vertical attaching 70 bars 13 are secured to the back wall of the body 10 and the lower ends of the bars are bolted or otherwise fastened, as at 14, to the outer edge portion or flange of the running board 15, while the upper terminals of the 75 bars 13 are extended inwardly, as at 16, to form brackets to be secured to the top irons 17, or the brackets 16 can be secured to the vehicle body in any suitable manner. The body 10 of the casing is thus fixed to 80 the vehicle, and a space is provided between the body 10 of the casing and the vehicle body which can be used as a luggage compartment or carrier for holding suit cases, 85 travelling bags, parcels, etc. 90

The bed frame comprises the sections 18 and 19 hingedly connected by the rule joints 20 whereby the frame can be "broken" upwardly, at the longitudinal center, and the sections folded together with their lower 100 surfaces confronting. The section 18 is hinged, as at 21, within the lower portion of the casing body 10, to permit said section 18 to swing upwardly and rearwardly 105 against the back of the casing, when folding the bed frame. The frame has a suitable flexible fabric 22 therein of linked, coiled or other fabricated wire, which fabric can fold with the frame.

The inner edge of the bed frame, being 110

hingedly connected with the body 10 of the casing, is supported from said casing body, and the outer section 19 of the bed frame is supported by legs 23 which are pivoted, as at 24, to the section 19. In order to automatically fold and unfold the legs 23, they have extensions 25 projecting above the pivots 24, and links 26 are pivoted to the extensions 25 and are also pivoted, as at 27, to the frame section 18 near the hinges or joints 20. The arrangement is such that when the sections 18 and 19 of the bed frame are swung together, the links 26 pushing on the extensions 25 of the legs, will swing the legs toward the hinges or joints 20, behind the links 26, as seen in Figs. 4 and 5. Conversely, when the frame is unfolded, the links 26 will cause the legs 23 to swing into position for supporting the section 19 of the bed frame. In this way, the legs 23 are automatically folded and unfolded with the bed frame, and said links also provide braces for holding the legs 23 upright when the bed frame is unfolded. The bed frame, when folded and swung into the body 10 of the casing, is held in such folded position by means of spring latches 29 secured to a depending flange 28 with which the upper portion of the rim of the body 10 is provided under the cover 11. The joints 20 of the bed frame are arranged to snap under and behind the latches 29 so as to hold the bed frame snugly in place within the casing. Said latches thus hold the opposite ends of the bed frame in place and prevent the frame from rattling or vibrating.

As a means for conveniently disengaging both latches 29 simultaneously from the bed frame, to release the bed frame for unfolding motion, a rock shaft 30 extends along the edge of the flange 28 and is journaled in bearings 31 carried by said flange. The rock shaft is provided at its opposite ends with cranks 32 extending across the latches 29, and said shaft has a crank handle 33 intermediate its ends. When the handle 33 is swung inwardly or rearwardly, the cranks 32 press the latches 29 inwardly and upwardly out of engagement from the bed frame, thereby enabling the frame to be moved out of the casing. One hand can be used for moving the handle 33, while the other hand is used for swinging the bed frame out of the casing.

The casing cover 11, when swung upwardly, provides part of a shelter or roof for the bed, and to complete such protection a leaf or plate 34 is hinged, as at 35, within the rim of the cover 11 at the free edge of said cover, so that the leaf 34 can be swung into the cover 11 when not in use, and can be swung downwardly and outwardly whereby the cover 11 and leaf 34 provide a gable roof or shelter, as seen in

Fig. 2. The leaf 34 has flanges 36 to contact with the rim of the cover 11 for limiting the movement of the cover and leaf when swung apart. In order to support the roof or shelter, props 37 are pivoted at their lower ends, as at 38, to the outer edge portion of the frame section 19, and have key-hole shaped openings 39 in their upper terminals to engage headed studs 40 provided within the rim of the leaf 34 at the free edge of said leaf. Thus, when the cover 11 is swung upwardly and the leaf 34 is swung forwardly, the props 37 can be swung upwardly and fastened to the leaf 34 by engaging the studs 40 rearwardly through the openings 39.

When the parts are unfolded and fastened as described, the bed is ready for use, and the roof or shelter is fixed so that it will not become displaced by the wind. The roof thus affords adequate and efficient protection against rain, the cover 11 and leaf 34 shedding rain inwardly and outwardly beyond the inner and outer edges of the bed frame, and curtains can be hung from the roof to enclose the bed frame if desired.

The structure can be folded together quickly and conveniently. Thus, the studs 40 are lifted and withdrawn from the openings 39, and the props 37 are swung downwardly along the outer edge of the bed frame. The leaf 34 is swung into the cover 11. The free edge portion of the leaf 34 preferably has a resilient catch 46 to frictionally engage a block 47 carried by the cover 11, in order to hold the leaf 34 in folded position, but permitting the leaf to be swung out of the cover when sufficient force is applied to overcome the friction of the catch 46. The bed frame is then broken upwardly and the sections 18 and 19 thereof folded together. At the same time, the bed frame is swung upwardly and rearwardly into the casing body 10, the joints 20 of the bed frame snapping under and behind the latches 29. The cover 11 is then swung downwardly against the body 10 to enclose the bed frame and other parts within the casing. The flanges 36 pass between the rim of the cover 11 and the links 26, as seen in Fig. 5, and the cover 11 is fastened to the body 10 by any suitable means. As shown, the rims of the body 10 and cover 11 have flanges 41 and 42, respectively, which can be secured together by the bolts 43 when a tight joint is desired.

The cover 11 of the casing can also be used as a table top when swung upwardly to horizontal position, as seen in Fig. 6. The cover or table top 11 is supported by braces 44, which, as shown, have their ends inserted through apertures in the flanges 41 and 42, although the braces can be attached to the body and cover of the casing in any suitable manner.

Fig. 7 shows a different latching arrangement for holding the bed frame in folded position. A hinged latch 29' is carried by the back of the body 10 to snap into engagement with a lug 29'' carried by the bed frame section 19, said latch being depressed by a leaf spring 29^a. A spring catch or latch 29^b is carried by the body 10 at the bottom thereof to snap into engagement with the frame section 19. Thus, the latch 29^b holds the lower portion of the frame section 19 in place, while the latch 29' holds the hinged portion of the frame in place. By releasing the catch 29^b and swinging the section 19 outwardly, the bed frame is automatically disengaged from the latch 29'. When the frame is doubled upwardly and folded, the lug 29'' snaps under the latch 29' while the frame 19 snaps over the latch 29^b.

Having thus described the invention, what is claimed as new is:—

1. A bed comprising a casing and a foldable bed frame arranged to fold into the casing, said casing including foldable members arranged to be unfolded above the bed frame, when the bed frame is unfolded, to provide a gable roof.

2. A bed comprising a casing, a foldable bed frame arranged to fold into the casing, said casing including foldable members arranged to be unfolded above the bed frame, when the bed frame is unfolded, to provide a gable roof, and means for supporting said members from the bed frame.

3. A bed comprising a casing and a foldable bed frame arranged to fold into the casing, said casing including hingedly connected members arranged to fold together and to be swung apart so as to provide a gable roof above the bed frame when the bed frame is unfolded.

4. A bed comprising a casing, a foldable bed frame arranged to fold into the casing, said casing including hingedly connected members arranged to fold together and to be swung apart so as to provide a

gable roof above the bed frame when the bed frame is unfolded, and props for supporting said members from the bed frame.

5. A bed comprising a casing having a body and a cover hingedly connected, a foldable bed frame arranged to fold into the body, said cover being arranged to swing upwardly, and a shelter member carried by the cover, said cover and member being arranged to be moved apart to provide a gable roof above the bed frame when the bed frame is unfolded.

6. A bed comprising a casing having a body and a cover hingedly connected, a foldable bed frame arranged to fold into the body, said cover being arranged to swing upwardly, a shelter member carried by the cover, said cover and member being arranged to be moved apart to provide a gable roof above the bed frame when the bed frame is unfolded, and means for supporting said member from the bed frame.

7. A bed comprising a casing having a body and a cover hingedly connected, a foldable bed frame arranged to fold into said body, the cover being arranged to swing upwardly, and a shelter member hingedly connected with the cover to fold against the cover, said member and cover being arranged to swing apart to provide a gable roof over the bed frame when the bed frame is unfolded.

8. A bed comprising a casing having a body and a cover hingedly connected, a foldable bed frame arranged to fold into said body, the cover being arranged to swing upwardly, and a shelter member hingedly connected with the cover to fold against the cover, said member and cover being arranged to swing apart to provide a gable roof over the bed frame when the bed frame is unfolded, and props for supporting said member from the bed frame.

In testimony whereof I hereunto affix my signature.

JAMES H. BOWLBY.
